United States Patent Office.

CHARLES W. CARDOT, OF FREDONIA, NEW YORK.

Letters Patent No. 64,745, dated May 14, 1867.

IMPROVEMENT IN ATTACHING THE DRAUGHT-POLE TO MOWING MACHINES.

The Schedule referred to in these Letters Patent and making part of the same.

TO ALL WHOM IT MAY CONCERN:

Be it known that I, CHARLES W. CARDOT, of Fredonia, county of Chautauqua, and State of New York, have invented a certain new and useful Improvement in Attaching the Draught-Pole to Mowing Machines; and I do hereby declare that the following is a full and exact description thereof, reference being had to the accompanying drawings, making a part of this specification, in which—

Figure I is a side elevation of the principal parts of a mowing machine with the draught-pole attached according to my improved method; and

Figure II is a plan of same.

The nature of this invention consists in the construction of a gear-frame and shoe, constructed as herein described, and journaled to the axle of the driving-wheels in a two-wheeled machine, and having the point of the attachment of the draught between the axle and the shoe.

In the accompanying drawings, A represents the axle or driving-shaft of the machine supported upon the driving-wheels A' in an ordinary manner. B represents the frame of the inner shoe supported by and hinged to the axle or driving-shaft, as seen at b¹ b². This frame is connected with the inner shoe D of the machine, to which shoe the finger-bar is attached. C is the draught-pole or tongue attached to the shoe-frame by a hinged connection at a point or points below the level of the driving-axle and between it and the shoe, as shown in the drawings at c c'.

Attempts have been made in various machines to overcome the drag of the shoe upon the ground by supporting it upon a roller or wheel, and other similar devices, but as yet lightness of draught has not been secured without constructing the machine so light and weak as to make it unfit for efficient service. My improvement overcomes the difficulty by causing the same power which is applied to drive the machine at the same time to lift upon the shoe and finger-bar, thus causing the shoe to slide much more easily upon the ground without enfeebling any part of the frame of the shoe or shoe by making it lighter than is necessary to stand the strain to which these parts are subjected. The draught of the team is by this improvement applied directly to relieve the pressure of the shoe and finger-bar upon the ground, which as a consequence produces a lighter draught of the machine, as a whole, without in any sense destroying or impairing its efficiency.

Having thus described my invention, what I claim, and desire to secure by Letters Patent, is—

In a two-wheeled machine having a gear-frame and shoe, constructed as herein described, and journaled to the axle of the driving-wheels, I claim the attachment of the draught-pole to such frame at a point or points between the axle and shoe, for the purpose and substantially as described.

CHAS. W. CARDOT.
